(57) **CLAIM**

The ornamental design for a display screen with graphical user interface, as shown and described.

DESCRIPTION

FIG. 1 is a front view of a display screen with graphical user interface according to our new design;

FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof;

FIG. 7 is a seventh embodiment thereof;

FIG. 8 is an eighth embodiment thereof; and,

FIG. 9 is a ninth embodiment thereof.

The outermost broken lines in all figures illustrate the display screen. The remaining broken lines in FIGS. 1, 4, and 7, illustrate portions of the graphical user interface. None of the broken lines form part of the claimed design.
